UNITED STATES PATENT OFFICE.

RENÉ THURY, OF GENEVA, SWITZERLAND, ASSIGNOR TO THE COMPAGNIE
DE L'INDUSTRIE ÉLECTRIQUE, OF SAME PLACE.

REGULATING DEVICE.

SPECIFICATION forming part of Letters Patent No. 529,570, dated November 20, 1894.

Application filed August 18, 1894. Serial No. 520,679. (No model.)

To all whom it may concern:

Be it known that I, RENÉ THURY, electrician, of Geneva, Switzerland, have invented certain new and useful Improvements in Regulating Devices, of which the following is a specification.

In the machines acted upon by any inconstant motive power whatever (water, steam, electricity, &c.) the reaction of the speed or intensity-regulator is advantageously transmitted to the valve or other distributing device by means of a self-acting intermediate device acting upon the said distributing device as soon as the smallest oscillation of the regulator proper occurs and without having the latter supporting directly the effort of resistance of the distributing device itself.

The object of the invention claimed is of the said kind and will be described below with reference to the accompanying drawings, in which—

Figure 1, is an elevation and partial section of the apparatus, and Fig. 2, is an elevation with the parts in a different position.

25 My regulating device is a very simple and quite automatic one and it is combined so as not to exceed the normal point of regulation as this occurs in most of the similar devices known till now.

30 My device is first composed of a lever L pivoted at O' to a fixed bearing S of any kind whatever and of a lever E, pivoted at O² to the same bearing S. The lever L is acted upon at l by the regulator proper (centrifugal 35 regulator, solenoid acting by attraction upon a piece of soft iron or the like) and the lever E receives a reciprocating motion by any suitable means whatever, for instance by a disk or crank M and a rod F.

40 To the point g of the lever E there are pivoted two clicks G' and G² which are caused by means of a spring G to engage the one with the teeth of wheel N' and the other with the teeth of a wheel N² which are both upon the axis O² acting upon the distributing device which is represented in the drawings by a switch Q moving upon suitable contact-pieces Q'. When the click G' is engaged in the teeth of wheel N' the switch Q moves in 45 the direction of the arrow 1 to the extent of one or more teeth of said wheel N' and when

the click G² is engaged in the teeth of wheel N², the said arm Q moves in the direction of the arrow 2, the pivot g of the said clicks G' and G² oscillating together with the lever E. 55 The latter is further provided with two pivots H' and H² bearing two three-armed levers, the arms h³ and h⁴ of which are connected together by means of a spring H which tends to bring the same back to their normal position shown in Fig. 1 of the drawings. The arms h³ and h⁴ of the said three-armed levers are intended to respectively catch the arms g' and g² of the clicks G' and G² in view of maintaining the same both out of reach 60 of the wheels N' and N² and extending the spring G. The arms h' and h² of the said three-armed levers are provided with projections passing into an opening I of the above described lever L and said opening is 65 provided with projections I' and I² against which abut according to the position in which the lever L is placed, either the arm h' or the arm h² when the latter are oscillating together with the lever E. Now when in an oscillation 70 from right to left the lever L having been lowered, the arm h' meets the projection I' the tooth h³ disengages the arm g' which allows the lever G' to engage the teeth of wheel N' as shown in Fig. 2. In its motion from 75 left to right the arm E rotates the wheels N' and N² which act directly upon the motor to cause the same to be automatically regulated. At the end of its following stroke from the right to the left the lever G' meets a stationary stop r which disengages the pawl from the teeth of N' and engages the arm g' with the arm h³ as soon as the lever L has returned to its normal position and separated I' from H' after the regulating action is performed. 80 When the lever L is lifted the opposite motion occurs by means of the levers h² h⁴ and G² acting upon the wheel N²; and when the lever L is in its normal position the arms h' and h² do not meet the projections I' and I² 85 and the clicks G' and G² remain consequently out of action. A small hand lever b is provided for securing the lever L in its normal position. To avoid an excess in the regulating action, that is to say a motion exceeding 90 the normal position of the regulator and to gradually stop the play of the switch Q (or

of the valve or other distributing device) when the same has been put into motion by one of the clicks G' or G^2 , I insert between the axis O^2 and the lever L the following 5 mechanism which is intended to transmit to the said lever L a reactionary movement from the axis O^2 . The latter carries a pinion O into which engages a rack Y pivoted in y and bearing a spring X rigidly fixed by one of its 10 ends to the said rack Y .

The lever L carries a cylinder L' which moves with it and in which there is a piston Z . The cylinder L' is filled with oil or another suitable liquid or fluid and the piston 15 is provided with a central hole and with some small radial holes c through which the said liquid or fluid may escape from one side of the piston to the other when the piston is moved in the cylinder. A rod a is located in 20 the tubular piston rod Z and has a tapering end to regulate the opening of the apertures c . In screwing or unscrewing the rod a one causes the opening through c to be enlarged or reduced and regulates thereby at will the 25 speed of the piston Z in its cylinder L' .

The end of the rod of the piston Z is connected to the other end of the above mentioned spring X so as to have the rack Y lifting or lowering the piston Z in the cylinder 30 L' as the shaft O^2 and its pinion oscillate in one direction or the other. The said rack Y tends thereby to lift or lower the piston Z and the action of the rack Y is transmitted to the lever L by means of the elastic intermediary 35 spring X and the piston Z playing in the liquid or fluid substance in the cylinder L' . The greater the movement of the pinion O the greater the tension of the spring X and the more the power exerted to move the piston Z 40 and the liquid or fluid in the cylinder L' seeks to pass through the apertures c . The action of the rack Y upon the lever L is always in opposite direction to that of the regulator acting upon the said regulator in the point l . It 45 therefore reacts upon the said regulator like

a constant brake tending to bring the lever L back to its normal position and acting with an intensity which is proportioned to the extent of rotation of the axis O^2 .

The percentage of the regulating device is 50 obtained by suitably regulating the openings c by the rod a .

Instead of affixing the spring X to the rack Y and the cylinder L' to the lever L one may reverse this arrangement or one may affix the 55 piston to the lever L and the spring X to the cylinder L' without altering the effect of the device.

Having thus fully described my invention, 60 I claim—

1. The combination in a regulating device of pawls, a lever for moving the pawls, ratchet wheels on which the pawls act in one direction or the other, mechanism for holding the pawls out of action, a lever for bringing the 65 pawls into action in one direction or the other, a cylinder and piston with a passage for the liquid and a regulating valve, and mechanism acting to move the piston or cylinder and the lever and control the action of the pawls substantially as specified.

2. The combination in a regulating device of spring pawls, a lever for moving the pawls, ratchet wheels on which the pawls act in one direction or the other, latch levers for holding 75 the pawls out of action, a lever for bringing the pawls into action in one direction or the other a cylinder and piston with a passage for the liquid to pass from one side of the piston to the other and a pinion, rack and lever connected with the piston or cylinder and acting upon the lever to control the action of the pawls, substantially as specified.

In testimony whereof I have signed my name to this specification in the presence of 85 two subscribing witnesses.

RENÉ THURY.
